UNITED STATES PATENT OFFICE.

SAMUEL DWORKIN, OF PHILADELPHIA, PENNSYLVANIA.

ELECTRIC IRON.

Application filed August 11, 1925. Serial No. 49,548.

My invention relates to electrically heated irons and consists of improved means for supporting an iron and effecting the application and cutting off of the electric current when 5 the iron is moved into various positions.

One object is to construct my invention in such manner that it can be readily used and will prevent disastrous results which have heretofore been caused by the heat of an iron 10 when unattended by an operator.

Another object is to so make my invention that it will allow the heating and cooling of the iron while the latter is in a position out of contact with the ironing board and tilted 15 in a position allowing the operator to conveniently ascertain the temperature thereof.

A further object is to so construct my invention in connection with an iron that it will possess the above advantages without requiring the operator to rotate or cause the 20 pushing of any switches.

These objects and other advantageous ends which will be set forth hereinafter, I attain in the following manner, reference being had 25 to the accompanying drawing in which

Figure 1 is a side elevation illustrating my invention applied to an electrically heated iron, showing the latter in a tilted and supported position which effects the heating 30 thereof,

Figure 2 is a side elevation showing the parts in the positions which they occupy while the iron is being used,

Figure 3 is a side elevation showing said iron in a rearwardly tilted position effecting the breaking of the electric current and the cooling of the iron,

Figure 4 is a rear elevation of said iron and parts, and

Figure 5 is a fragmentary elevation of my invention with certain of the parts slightly changed in shape from those illustrated in Figures 1 to 4, and allowing the iron to be tilted rearward to a greater extent than illustrated in Figure 3.

Referring to the drawing, 6 represents an iron which may be of any of the well known forms including a heating agent (not illustrated) to which electric current is supplied 50 through the medium of two connecting posts 7 and 8 which project outwardly through the top of the body portion 9 of the iron to the rear of the handle 10.

I have illustrated an electric switch 11 55 which is claimed per se in my pending application for United States Patent, Serial No.

632,821, allowed July 20th, 1925, and I have illustrated said switch in detachable connection with the posts 7 and 8 at a position to the rear of the handle 10, said switch, as illustrated in the present application, including a casing 12 having therein post connectors or contacts 13 and 14 for the respective posts 7 and 8. The contact 13 is directly connected with a feed wire or conductor 15, while the contact 14 is in connection with an abutment member 16 which is spaced below the bottom of a tubular terminal or guiding member 17. The terminal 17 is electrically connected to an electric conduit feed wire 18, said conductors 15 and 18 acting as the feed wires for electric current from any suitable source and enter the casing 12 as clearly illustrated. A metallic gravitating member 19, in the form of a ball, is adapted to roll within the 75 tubular terminal 17 and when the latter is in an upright or inclined position as clearly shown in Figures 1, 2 and 4, the ball will move by gravity into engagement with the abutment 16, a portion of said gravitating 80 member 19 still remaining within the tubular terminal 17 and in contact therewith, to complete an electric circuit through the iron to effect the heating thereof.

The parts above specifically described are 85 not claimed per se in the present application, but are illustrated and described as showing a convenient and suitable form of electric switching means which will be effective when used in connection with means now to be described for effecting the supporting of the iron in various positions and for effecting the heating and cooling of the iron while being supported in positions in which the hot part of the iron is out of contact with the 90 ironing board.

A supporting device or stand 20 has a portion or member 21, the upper part of which is secured to the rear face 22 of the body 9 of the iron by a screw 23. The member 21 is 100 preferably made comparatively wide as shown in Figure 4 with its lower part 24 rolled or turned to provide a bearing for a pivot or hinge pin 25. The part 24 is positioned in spaced relation to and rearward 105 of the back of the iron and above the level of the ironing surface 26 of the base 27 of the iron when the iron is in operating position as clearly shown in Figure 2. Furthermore, the part 24 of the member 21 is discontinued 110 within its length to provide a recess or notch 28 as clearly shown in Figure 4, said notch

serving to bifurcate the lower part of the member 21 to provide clearance space for a member 29 now to be described.

The member 29 can be made of sheet metal bent to form two converging portions 30 and 31, the portion 31 being curved adjacent its free end as shown at 32. The member 29 is adapted to swing freely on the pivot or hinge pin 25 and can be moved into a position as shown in Figure 2 and held by means of a spring 33. The spring 33 is in the form of a strip, one end of which is secured by the screw 23, while the other end is free and adapted to be engaged by the curved part 32 of the member 29 so that during movement of the member 29, the part 32 will serve to deflect the upper curved end 34 of the spring until it passes thereunder, after which the latter will return to its normal position and hold the member 29 in the position as shown in Figure 2. It may be here stated that in order to again release the part 32 of the member 29, it is necessary to manually move the upper end 34 of the spring 33 to free the part 32, after which the member 29 can swing on the pivot pin 25.

The material of the member 21 is preferably extended upward and bent to form a reinforcing guard and brace 37 for the lower end of the switch casing 12, this brace having its lower edge resting on the top surface of the body portion 9 of the iron.

It will be noted, as clearly shown in Figure 1, that the member 29 when released from the spring 33 can be positioned to rest upright on the ironing board, the surface level of which is indicated by the line 35, and by swinging the iron forwardly, the rear portion of the base 27 will engage the portion 30 of the member 29 thereby supporting the iron with the ironing surface tilted forwardly, the extent of tilting of the iron being sufficient to cause the gravitating member 19 to engage the abutment member 16 and thereby complete an electric circuit through the iron to heat the same. When the iron has been heated to the proper degree for ironing purposes, the operator by lifting the iron will allow the member 29 to swing downwardly and then by rocking the iron on the part 24 into the position shown in Figure 3, the part 32 will engage the spring 33 and become fastened so that the iron can then be moved into the ironing position as shown in Figure 2.

If for any purpose it is necessary for the operator to discontinue ironing, or if the operator is temporarily called away, it is merely necessary for her to tilt the iron on the portion 24 of the stand either into the position shown in Figure 3 or into the full line position shown in Figure 5 and the iron will be supported in such rearwardly tilted position and the gravitating member 19 will move within the tubular terminal 17 and out of engagement with the abutment member 16,

thereby breaking the electric circuit and consequently discontinuing heating of the iron. When in said latter position, the base 27 is held in a position remote from the ironing board and the iron will cool. When it is desired to again use the iron, it is merely necessary to release the member 29 from the spring 33 and allow the member 29 to be moved into the position shown in Figure 1 where it will again support the iron in a forwardly tilted position.

By shaping the parts as shown in Figure 5, the iron can be tilted into its extreme rearward position to effect the breaking of the electric circuit and it will rest upon the part 24 and the end portion 36 of the switch casting 12, thus insuring a stable mounting or support for the iron.

From the foregoing description and as illustrated in the drawing, it is obvious that it is unnecessary for the operator to rotate or cause the pushing of any switches if it is necessary for the operator to temporarily discontinue the ironing operation. The mere tilting of the iron rearwardly will cause the discontinuation of the electric current and such a tilting action is an easy one to perform and the operator will know that if she tilts the iron rearwardly as above described that there is nothing to fear since the current is cut off automatically by such tilting and that the iron will cool.

Having thus described my invention what I claim as new and desire to secure by Letters Patent is:

1. The combination with an iron of a stand including a portion providing a tilting support for the iron to hold the base clear of the ironing board, said stand having a hinged portion adapted to be swung forwardly under the base of the iron to support the bottom ironing surface in a forwardly tilted position.

2. The combination of an iron; and a stand, said stand including a portion secured to the iron and projecting rearwardly to provide a rocking support, said stand also including a pivoted portion movable forwardly under the iron to support it.

3. The combination of an iron; and a stand, said stand including a portion secured to the iron and projecting rearwardly to provide a rocking support, said stand also including a pivoted portion movable forwardly under the iron, said pivoted portion being bent to provide a raised support for the iron when swung forwardly thereunder.

4. The combination of an iron; and a stand, said stand including a portion secured to the iron and projecting rearwardly to provide a rocking support, said stand also including a pivoted portion movable forwardly under the iron, said pivoted portion being bent to provide a raised support for the iron when swung forwardly thereunder, the pivot connection being so positioned relatively to

the base of the iron as to cause said iron to be supported in a tilted position.

5. The combination of an iron; and a stand connected to the iron and having a portion movable under the iron to support the latter in a tilted position.

6. The combination of an iron; and a stand connected to the iron and having a pivoted portion adapted to swing under the bottom ironing surface of the iron and support said surface in an inclined tilted position.

7. The combination of an iron; and a stand connected to the iron and having a pivoted portion adapted to swing under the iron and support the latter in a tilted position; and readily releasing means for holding said portion in a position out of the way of the bottom ironing surface when the iron is being moved for ironing purposes.

In testimony whereof, I have signed my name to this specification.

SAMUEL DWORKEIN.
